UNITED STATES PATENT OFFICE.

LA FAYETTE WILDERMUTH, OF COLUMBUS, OHIO.

WIRE-COILING MACHINE.

SPECIFICATION forming part of Letters Patent No. 296,806, dated April 15, 1884.

Application filed September 4, 1883. (No model.)

To all whom it may concern:

Be it known that I, LA FAYETTE WILDERMUTH, of Columbus, county of Franklin, State of Ohio, have invented a new and useful Improvement in Wire-Coiling Machines, of which the following is a full, clear, and exact description, reference being had to the accompanying drawings, making a part of this specification, in which—

10 Figure 1 is a perspective view of a wire-coiling machine with my improvements attached. Fig. 2 is a vertical section of the same. Fig. 3 is a separate view of the twisted bit. Fig. 4 is a separate view of the cam-slide which 15 operates the top plate. Fig. 5 is a detached view of the top block of the former. Fig. 6 is a detached view of the spring or of the forms, &c. Figs. 7, 8, 9, and 10 illustrate the manner of forming the bends between the 20 coiled springs.

My invention has reference to machines for coiling wire springs, and is an improvement on my Patent No. 245,683, issued to me August 16, 1881; and it consists in the several combinations of devices, hereinafter explained and 25 claimed.

To enable others skilled in the art to make and use my invention, I will proceed to describe the exact manner in which I have carried it out.

30 In the drawings, A represents a hollow post, made in two sections and united together. Near the top of the post A is placed the mandrel B, constructed and operated by the crank E', as described in my former patent. On the top of the post A, I secure the plate a, grooved on its periphery, and slotted on its upper face, as shown in Fig. 3. On the upper face of this plate I also provide two vertical pins, b, of 35 unequal diameters, around which eyes or loops of different sizes may be easily formed in the wire. The top plate, a, is secured to the upper end of a twisted bit, C, which extends down in the hollow post and passes through 40 the cam-slide c, which is caused to rise and fall vertically, and consequently causes the top plate, a, to make a revolution each time the cam-slide passes up or down, reversing the direction of the plate's revolution as you 45 reverse the direction of the cam-slide. By the motion thus given to the plate a, provided 50 with the groove a', (see Figs. 7, 8, 9, 10,) it

is evident that bends or eyes can be readily formed in the wire-connections between the coiled springs, as shown in Fig. 6. The rectangular lugs c' of the cam-slide fit in the vertical slots D in the post A, and these slots act as guides to keep the slide level and force it to travel vertically, which consequently forces the twisted bit C and plate a to revolve, 55 as before described. The cam-slide is attached by rods d or by any other convenient and suitable means to the treadle-lever E, so that when the treadle-lever is forced down it carries down also the cam-slide and causes a revolution of the plate a. When the pressure is removed from the treadle-lever E, the coiled spring F forces up the lever and cam-slide, and causes the plate a to revolve in the opposite direction, and reversing the bend in the spring 60 connection, as shown in Fig. 6. The spring F may be made as shown in my patent before referred to. Connected with the treadle-lever by means of a rod, e, is a lever cutter-blade, G, provided with a notched cutting-edge at g, 65 for cutting off the wire.

On the side of the post A, I also construct a former for pressing and finishing up the spring after it has been taken from the mandrel. The former consists of the stationary lower block, 80 H, permanently secured to the side of the post A. From this block rise two guide-rods, h h, which, near their top, are bent at right angles and rigidly secured to the post. On these guide-rods slides the upper block, I, which is 85 connected by bars i i to the treadle-lever E, so that when the lever is depressed the block I may be brought down level upon the block H by means of the treadle-lever. The lower face of the upper block, I, is grooved, as 90 shown in Fig. 5, to hold the foot of the spring so that the block may press the spring level without being interfered with by the foot. Thus, between the guide-rods h h and the wall of the post, the spring is kept from spreading 95 while the block I presses it into proper shape, the width of the spring taking up the space between the guide-rods and the post.

It will be seen that by this construction of my improved machine I operate the revolving 100 plate a for looping and forming eyes on the springs, the lever carrying the cutter-blades, and the former, all by the single treadle-lever E.

Having thus explained my invention, what I

claim as new, and desire to secure by Letters Patent, is—

1. The hollow post A and mandrel B, in combination with the revoluble plate *a*, the 5 twisted bit C, cam-slide *c*, treadle-rod *d*, and treadle-lever E, all constructed to operate substantially as and for the purpose set forth.

2. The hollow post A and mandrel B, in combination with the blocks H and I, the guide- 10 rods *h h*, bars *i i*, and treadle-lever E, all constructed to operate substantially as and for the purpose set forth.

3. The hollow post A and mandrel B, in combination with the revoluble plate *a*, provided with the groove *a'* and pin *b*, the twisted 15 bit C, cam-slide *c*, rod *d*, cutter-blade G, rod *e*, coiled spring F, and treadle E, all constructed to operate substantially as and for the purpose set forth.

LA FAYETTE WILDERMUTH.
